PRINTING-TELEGRAPH SYSTEM.

Application filed July 28, 1927. Serial No. 208,911.

In printing telegraph systems it is common practice to use currents of different strengths to control the operation of the receiver, the different strengths being obtained by means of one or more relay mechanisms which serve to cut resistance into and out of the transmission circuit. For example, in systems using receivers of the "stock ticker" type, the imprints are made in two lines on a paper tape past a type wheel having two rows of characters. Either row of characters can be selected for printing, the selection, or, as it is commonly known, the "shift", being effected either by mechanical means, which may be of the kind described in prior Patent No. 1,558,610, issued October 27, 1925, to Stock Quotation Telegraph Company, or by suitable electromagnetic means. In systems in which a separate transmission circuit is employed for controlling the "magnetic shift" the accomplishment of the desired result is easy enough but in so called "one-wire" systems, in which all current must be sent over a single circuit the problem is difficult in practice, however simple and easy it may be in theory. In our copending application Serial No. 144,230, filed October 26, 1926, we have described a one-wire system in which a magnetic shift is employed. In that system depression of a transmitter key corresponding to a character in one row of type wheel characters causes to be sent over the line to the distant ticker a current strong enough to actuate the type-wheel escapement, by which rotation of the type wheel is controlled, but too weak to actuate the ticker shift-mechanism. When, however, a key is depressed corresponding to a character in the other row on the ticker type wheel, current is sent over the line strong enough to actuate not only the escapement but also the shift mechanism and accordingly the imprint is made from the said other row of characters. In either case the printing is effected by a "press" magnet which must develop sufficient power to do its work, and hence it is desirable to have the current through the press magnet constant and sufficient in strength to give the requisite amount of power. Accordingly it is desirable to employ at the ticker a local circuit for the press magnet, containing an adequate source of current, and to control

such local circuit by means of a relay in or controlled by the transmission circuit. Our present invention, although capable of advantageous use for other purposes, relates primarily to this relay control of the local circuit, and its chief object is to provide a relay system of unfailing reliability, sensitive to the weakest current intended to operate it, and withal simple and rugged in construction so as to be capable of operating for long periods without attention. To this and other ends the invention comprises the novel features and combinations hereinafter described.

In the preferred form of the invention we provide two relays to control the local circuit, one of which is sensitive to the weak current (and hence to strong current also) while the other is sensitive only to the strong current, but these relays are interconnected in such manner that at appropriate times the "strong" relay prevents effective operation of the other or "weak" relay. Two embodiments of this form of the invention are illustrated in the accompanying drawing, in which

Fig. 1 is a plan view of the preferred relay mechanism itself, and Fig. 2 is a wiring diagram of the ticker end of the printing telegraph system.

Fig. 3 is a diagram illustrating another embodiment of the preferred form of the invention.

Fig. 4 is a diagram showing another form of the invention.

The parts shown in Fig. 1 are conveniently mounted on a base board 10 and comprise a pair of relays S, W, connected in series in the transmission line 11, Fig. 2, which also includes, in series, the ticker escapement magnets 12 and the ticker shift magnet 13. The ticker, indicated diagrammatically at 14, and the shift mechanism represented by magnet 13, may be of the type shown in the aforesaid copending application Serial No. 144,230.

Relay magnet S, which requires a strong current for adequate energization, has a pivoted armature 15, urged outwardly or away from the magnet by a spring 16 and provided with a spring contact 17 adapted to cooperate with an adjustable fixed contact 18. An adjustable stop 19 limits the outward swing of the armature. Relay

magnet W, sensitive to weak current, has a similar pivoted armature 20, provided with a returning spring 20^a and equipped with a spring contact 21 cooperating with a yielding or shiftable contact 22. The two armatures are electrically in parallel and are connected to the local source of current, in the present instance the supply mains 23, 24, and the neutral or third wire 25. Contacts

- 10 18 and 22 are likewise connected in parallel, and they are also connected to the main 23 through the ticker press magnet 26. Across the armatures and their associated contacts 18, 22 is a condenser 27, in series 15 with a resistance R_1 , which may be an ordinary lamp (not shown) in a receptacle 28, Fig. 1. A receptacle 29 is shown for a similar resistance R_2 in the press magnet local circuit.

Suppose, now, that the current impulses of alternating polarity sent over the transmission line 11 are weak. Current then flows through wire 11, relays W, S, wire 30, ticker escapement magnets 12, and ticker shift magnet 13. The current being weak, the latter magnet is not energized sufficiently by the prolonged final impulse to actuate the shift mechanism, nor does magnet S respond to the weak current and accordingly 30 its armature 15, Fig. 2, remains out of engagement with contact 18. But magnet W responds to the final impulse (which is prolonged for the purpose) and swings its armature 20 over against contact 22. Local 35 current then flows from main 23 through wire 31, press magnet 26, wires 32, 33 contact 22, armature 20 and wire 34 to the third wire 25. This energizes the press magnet and the imprint is made. When 40 current ceases to flow in the line 11 the relay W is deenergized and the local circuit is opened.

Suppose, now, that strong impulses are transmitted. In that case both magnets S, 45 W respond, the shift magnet 13 also responds, and on the final prolonged impulse the press magnet local circuit would be closed by both armatures. Then when the line 11 is opened (at the transmitter, not shown), to deenergize the press magnet by causing the relay system to open the local circuit, both relays should be deenergized 50 instantly. If, however, spring 20^a is so adjusted as to permit actuation of armature 20 by magnet W when energized by weak current the spring tension may be too weak to return the armature quickly enough after the magnet has been over-energized, so to speak, by strong current. In other words, 55 the armature sometimes "sticks" momentarily, thus keeping the local circuit closed and thereby causing the printing platen (not shown) to hold the typewheel. This throws the receiver out of unison with the transmitter, and it will be readily seen that such

effects militate seriously against the smoothness and reliability of operation which are so important in a printing telegraph system, especially when the system is used for reporting sales on a stock exchange, for example. In any case the adjustment of the returning spring is more or less critical, and change in its resiliency, due to temperature variation or other cause, may vitiate the adjustment and make the operation of the receiver uncertain.

The difficulty outlined above is obviated by interconnecting the two relays S, W, in such manner that whenever the armature of the "strong" relay is actuated the contacts 80 of the "weak" relay are positively separated. In the present instance the interconnecting means are in the form of an insulating rod 36 slidably mounted in a guide block 37, between the armature 17 of the strong relay S and the yielding contact 22 of the weak relay W. Now suppose that the strong impulses (alternating in polarity) are sent over the line 11. When the final impulse is prolonged to effect the 85 printing, both armatures are actuated and swung toward their cooperating contacts 18, 22. The press magnet local circuit is thereby closed at contact 18 by the strong relay S; but as the armature 15 swings over, it shifts the rod 36 rightwardly and the latter in turn bends the spring contact 22 away from armature 20, thus preventing engagement with the spring contact. The imprint having been made, the line is opened 90 and current thereupon ceases to flow through the relays. The strong spring of magnet S at once returns the armature 15 to open position, which breaks the press magnet local circuit. The latter magnet being thus 95 deenergized the ticker platen (not shown) swings away from the typewheel (not shown) and the typewheel is free to be rotated for the next printing operation. As armature 15 swings back to open circuit 100 position, armature 20 may do likewise at the same time, but suppose it does not. In that case no harm is done, inasmuch as the actuation of the rod 36 had prevented closing the local circuit at contact 22. As armature 15 swings away from contact 18, spring contact 22 swings back toward armature 20, which we are assuming has "stuck" in closed (or rightward) position, and might 105 eventually engage the armature thereby closing the press magnet local circuit again. It does not, however, for the reason that as the contact 22 swings toward the left the field of magnet W is decreasing in strength, and before the contact 22 reaches the sticking armature 20 the field has decreased sufficiently to let the spring 20^a act and throw the armature back to open circuit position. The ultimate result is the same as if magnet 110 W could not respond effectively, if at all, to 115

strong current; or as if it would release as quickly after strong current as after weak current.

Stating the conditions in other words, it is important that if at any time both relays can simultaneously close the press magnet local circuit, both shall "let go" instantly and simultaneously, or that, if a single relay were used, it be not only equally sensitive to weak and strong current but also be capable of instant deenergization after strong current as well as after weak current. These desiderata are difficult of accomplishment, especially where, as in stock ticker work, unfailing reliability of operation is a prime essential. The difficulty, however, is obviated in the relay system illustrated, as described above.

An eccentric stop 38 limits the leftward movement or swing of armature 20. Means of conventional type for adjustment of the tension of springs 16, 20^a, may also be provided, so that by adjustment of the springs and stops the best operating conditions can be obtained.

In the system shown in Fig. 3 the interconnection between the two relays is electrical rather than mechanical, in that when the relay S, which requires strong current for energization, actuates its armature the latter opens the circuit of relay W, which can operate on weak current. For this purpose armature 25^a of relay S is provided with a bridge piece 40, insulated from the rest of the armature and adapted to span a pair of contacts 41 in series with relay W, which latter is in parallel (through contacts 41) with relay S. Weak current entering by wire 42 flows through wire 43, relay W, wire 44, contacts 41 and bridge 40 and wire 45; also from wire 42 through 42^a and relay S to wire 46; thence through escapement magnets 12, wire 47, and shift magnet 13 to the neutral or third wire 25. Relay W, thus energized, swings its armature 20^a over against contact 48, thus establishing a local circuit for the press magnet 26 from main 23, through wire 49, magnet 26, wires 50, 51, contact 48, armature 20^a, and wire 52 to the third wire 25. It will of course be understood that the final weak impulse must be prolonged in order to energize relay W, as in the system illustrated in Figs. 1 and 2.

If the current entering at 42 is strong, then on the final impulse both relays S and W, are energized, but the actuation of armature 25^a withdraws the bridge 40 from contacts 41, thereby breaking the circuit of relay W and at the same time establishing the press magnet local circuit by way of wire 50, contact 53, armature 25^a, and wires 54, 52 to third wire 25. It will thus be seen that when the final impulse is strong, relay W is not energized and hence there is no

danger of its armature sticking on contact 48, which would keep the press local circuit closed, when the line circuit is opened at the transmitter.

In the system shown in Fig. 4 the shift magnet performs in part the function of the strong relay, in that it so controls the other relay, W, that the latter's armature 25^b will not stick and thus keep the press local circuit closed when strong current has been sent over the transmission circuit. For this purpose the shift armature 56 is provided with a finger 57 which, when the shift magnet 13 is energized by strong current, closes spring contacts 58 and thereby lays across relay W a shunt having sufficient resistance R₃ to prevent shorting out the relay entirely but still to take so much of the current as to leave only enough for energizing magnet W without causing its armature to stick. Suppose, now, that the current entering by wire 59 is weak. Shift magnet 13 is therefore not energized by the prolonged final impulse and hence contacts 58 remain open, thus giving relay W the full line current. The relay is accordingly energized and its armature closes the local circuit of press magnet 14 at contact 60. On the other hand if the line current is strong, the final impulse energizes the shift magnet 13, which closes the shunt contacts 58 as described, thus depriving relay W of current but leaving it enough for sure energization to close the press local circuit at contact 60. In this way relay W always has enough current to insure its operation at the proper time but never enough to cause sticking.

It is to be understood that the invention is not limited to the specific form herein described but may be embodied in other forms without departure from its spirit.

We claim—

1. In a printing telegraph system, in combination, a normally open local circuit, relay mechanism having electromagnetic actuating means inherently responsive to both strong and weak current to close said local circuit, and having automatic actuating means for causing opening of the local circuit when current ceases to flow in said electromagnetic means; and means distinct from said automatic means and responsive only to strong current to insure instant opening of the local circuit when strong current ceases to flow.

2. In a printing telegraph system, in combination, a normally open local circuit, circuit-closing relay mechanism having electromagnetically actuated devices responsive one to both strong and weak current and one to strong current only, automatic actuating means for the relay mechanism for causing opening of the local circuit when current ceases to flow in said relay mechanism, and means responsive to strong current and co-

operating with the device which is responsive to both strong and weak current, to insure instant opening of the local circuit when strong current ceases to flow.

5. In a printing telegraph system, in combination, a local circuit, a relay to control said local circuit and responsive only to strong current, a relay to control said local circuit and responsive to weak current, and 10 means actuated by the first relay to prevent effective response of the second relay to strong current.

6. In a printing telegraph system, in combination, a relay magnet responsive only to 15 strong current, an armature therefor, a relay magnet responsive to weak current, an armature therefor, a local circuit connected with both said armatures to be closed and opened by each, and means actuated by the 20 first magnet to prevent effective response of the second magnet to strong current.

7. In a printing telegraph system, in combination, a local circuit, a relay magnet, responsive only to strong current, an armature 25 therefor connected with the local circuit to close and open the same, a relay magnet responsive to weak current, an armature therefor connected with the local circuit to close and open the same, and means actuated 30 by the first armature to prevent effective actuation of the second armature when its magnet is energized by strong current.

8. In a printing telegraph system, in combination, a local circuit, a strong-current relay having an armature connected with the local circuit to close and open the same on strong current, a relay in series with the first and having an armature in parallel with the first armature to close and open the local 40 circuit on weak current, and means actuated by the first armature to prevent closing of the local circuit by the second armature on strong current.

9. In a printing telegraph system, in combination, a transmission circuit, a receiver local circuit, a relay having a magnet connected with the transmission circuit for energization by strong current only in said transmission circuit and having an armature 50 connected with the local circuit to close and open the same, a relay having a magnet connected with the transmission circuit for energization by weak current therein and having an armature connected with the local 55 circuit to close and open the same, and means actuated by the first relay and cooperating with the second to prevent closing of the local circuit on strong current in the transmission circuit.

8. In a printing telegraph system, in combination, a transmission circuit, a receiver local circuit, a relay having a magnet connected with the transmission circuit for energization only by strong current therein and having a pair of relatively movable contacts 60 actuated by the magnet to close and open the local circuit, a relay having a magnet connected with the transmission circuit for energization by weak current therein and having a pair of relatively movable contacts 65 actuated by the magnet to close and open the local circuit, and means actuated by a contact of the first pair and cooperating with a contact of the second pair to shift the latter contact out of the range of movement of the other contact of the second pair and thereby prevent closing of the second pair when the first relay is actuated.

9. In a printing telegraph system, in combination, a transmission circuit, a relay magnet connected with the transmission circuit and energizable only by strong current therein, an armature arranged for actuation by said magnet and connected in the local circuit, a fixed contact connected in the local circuit and cooperating with said armature to close and open the local circuit, a relay magnet connected with the transmission circuit and energizable by weak current therein, an armature arranged for actuation by the second relay and connected in the local circuit, a shiftable contact connected in the local circuit and normally positioned for engagement with the second armature to close and open the local circuit, and a member actuated by the first armature and cooperating with said shiftable contact to displace the same, and thereby prevent engagement by the cooperating armature, when the first relay magnet is energized.

10. In a printing telegraph system, a pair of relays having magnets in series and armatures in parallel to open and close a local circuit, one relay being capable of actuation on strong current only and the other on weak current, a normally fixed contact for the weak relay shiftable out of range of the armature of the weak relay, and a movable rod between the armature of the strong relay and the shiftable contact of the other to shift the latter when the strong relay armature is actuated, whereby to prevent closing of the local circuit by the weak relay on strong current.

In testimony whereof we hereto affix our 115 signatures.

GEORGE S. HILTZ.
WILLIAM F. PURCELL.
